PAGE 2

FIG. 4.

FIG. 5.

FIG. 1 is a perspective view, partly schematic, of a pneumatic tire in which the characteristic feature of the design resides in the tread and buttress pattern shown in part only, it being understood that the tread and buttress pattern represented by the shaded portion of the design is repeated throughout the circumference of the tire, as shown schematically by solid lines, and that the identical buttress pattern appears on the opposite side of the tire; FIG. 2 is an enlarged, fragmentary plan view of the tread of FIG. 1;

FIG. 3 is an enlarged, fragmentary plan view of the buttress of FIG. 1;

FIG. 4 is a fragmentary sectional view of the tread, taken substantially on the plane indicated by line 4—4 of FIG. 2; and

FIG. 5 is a fragmentary sectional view of the buttress, taken substantially on the plane indicated by line 5—5 of FIG. 3.

I claim:

The ornamental design for a pneumatic tire, substantially as shown and described.
